METAL FORMING MACHINE

Henry A. Berliner, Washington, D. C., assignor
by mesne assignments, to Engineering and Re-
search Corporation, Riverdale, Md., a corpora-
tion of Maryland

Application October 7, 1938, Serial No. 233,726

2 Claims. (Cl. 153—48)

This invention relates to metal forming machines and more particularly to improved work holding clamps and operating means therefor.

One of the objects is to provide a metal forming machine having a work holding clamp which will hold the work securely. According to one important feature the strain on the work tends to tighten the clamp so that the work will be held tighter as the strain increases.

Another object of the invention is to provide a metal working machine having a work holding clamp which may be operated by fluid pressure. The fluid pressure preferably gives the clamp an initial set and further tightening is effected by strain on the work piece itself.

Still another object of the invention is to provide a metal working machine having a plurality of adjustably mounted clamps to accommodate work pieces of different shapes. According to one feature of the invention the clamps are operated by fluid pressure supplied through flexible connections and controllable to operate the clamps separately or simultaneously.

Other objects, advantages and novel features of the invention will be apparent from the following description of the accompanying drawings, in which:

Figure 1 is a partial side elevation of a machine embodying the invention;

Figure 2 is a partial end view showing the clamps;

Figure 3 is an enlarged front view of a clamp;

Figure 4 is a section on the line 4—4 of Figure 3; and

Figure 5 is a partial section on the line 5—5 of Figure 4.

The invention is illustrated in a machine for forming sheet metal into irregular shapes, as for example to form parts for aircraft or the like. As best seen in Figure 1 a base 10 supports a pair of elongated support beams 12 extending transversely of the base and adjustable longitudinally thereof. A plurality of clamps 14 are mounted on each of the beams 12 and grip the opposite ends of a metal sheet 16.

Between the beams 12 there is arranged a vertically movable hydraulic piston 18 having a platform 20 removably secured to its upper end. A male form 22 which may be made of wood or other suitable material is mounted on the platform 20 in a position to engage the sheet 16. While the form 22 shown in Figure 1 is of a very simple shape it will be understood that forms of any desired shape or size can be employed.

In use the metal sheet 16 is clamped in the

clamps 14 and pressure is applied to the piston 18 to raise it. This causes the form 22 to be pressed up into the sheet, causing the sheet to be stretched and bent into the shape of the form.

In order to secure the clamps 14 to the beams 12, the beams are formed with central slots 24 (Figure 4) and bolts 26 having enlarged lower ends 28 are extended through the slots and through suitable bosses 30 on the clamps. The ends 28 engage the sides of slots 24 and nuts 32 are provided to draw the clamps rigidly against the beams 12. By loosening the nuts 32 the clamps can be adjusted to any desired position on the beams to accommodate a work piece of irregular edge outline and to assist in this adjustment screws 34 are provided in the clamps engaging flanges 36 on the beams.

At its upper end each of the clamp bodies 14 is formed with an outwardly converging elongated slot. The converging side walls of the slot are preferably faced with hard metal bearing strips 38 serving as one bearing surface for anti-friction rollers 42. Guard strips 40 are preferably provided at the top of the slots to keep dirt chips and the like from falling into the rollers 42. A pair of elongated tapered clamp jaws 44 is mounted in each slot with one surface engaging the rollers 42 and the inner facing surfaces substantially parallel to receive a work piece between them. Preferably the inner surfaces are roughened to grip a work piece more securely. End plates 45 on the clamp body 14 serve to prevent endwise movement of the jaws in the slots, plates 40 holding them against coming out the top.

According to one important feature of the invention the inner clamping surfaces of the jaws are not exactly parallel but diverge outwardly very slightly. Thus a strip clamped in the jaws is clamped hardest at its inner edge with the clamping force progressively decreasing toward the outer edge of the jaws. This avoids stress concentration in the strip at the outer edges of the jaws and eliminates the tendency of the sheet to tear at this point.

One desirable manner of obtaining this result is to proportion the jaws and the body so that the body at the sides of the slots will yield slightly to relieve the pressure at the outer edge of the jaws. Since the body will yield first at the outer portion this gives the desired action, the body being stiff enough to give a gripping action throughout the major portion of the jaw area.

The jaws 44 are operated by pistons 46 mount-

ed in cylinders 48 in the body and connected at their lower ends to fluid passages 50. Preferably two or more spaced cylinders and pistons are provided in each clamp to operate the elongated clamp jaws uniformly throughout their length. Bores 52 are provided in the clamp bodies terminating in nipples 54 to conduct operating fluid into the passages 50.

Compressed air or other suitable operating fluid is supplied to the clamps through a manifold pipe 56 connected to a suitable source of fluid through a master valve 58. A plurality of spaced nipples controlled by individual control valves 60 are provided in the manifold 56 connected to the nipples 54 through flexible conduits 62.

This arrangement makes it possible to operate all or any selected group of the clamps simultaneously or to operate the clamps individually. For the first mode of operation all or a selected group of the valves 60 may be opened and then the master valve 58 may be opened to supply fluid simultaneously to all of the clamps whose valves 60 are open. To operate the clamps individually the master valve 58 may be opened and the valves 60 may then be opened separately as desired.

When fluid pressure is supplied to a clamp the pistons 46 will be moved upwardly to move the jaws upwardly in the slots. As the jaws move they will be cammed together to grip a work piece tightly between them and as tension is applied to the work piece it will tend to pull the jaws still farther out so that they will be cammed still tighter together. Thus the greater the tension applied on the work piece the tighter the jaws will grip it. When the tension is removed and the fluid pressure is relieved the jaws will drop down to release the work piece so that it can easily be removed.

The pistons 46 need not be extremely powerful but should exert enough force so that the jaws will straighten out any small waves or kinks in the edge of a sheet metal work piece. In this way the jaws bear on the work piece throughout their full length and provide a firm initial grip so that the piece will not slip when tension is applied as might happen if the jaws bore on only one or two high spots.

While the invention has been described and illustrated in connection with a particular metal forming machine it will be understood that it might be applied equally well to other uses, as for example to a draw bench or the like, and that other changes might be made therein. Ref- 50

55

erence will therefore be had to the appended claims for a determination of the scope of the invention.

What is claimed is:

1. In a sheet metal forming machine of the type in which the opposite edges of a sheet are clamped to spaced straight beams and the sheet is subjected to a stretching operation between the beams, means for clamping each edge of a sheet to a beam comprising a plurality of identical clamp devices adjustably mounted side by side along the length of each beam, each of said clamp devices comprising a body having an upper surface, a recess extending through the body which is of substantially uniform transverse cross-section with the longitudinal axis of the recess substantially parallel to the beam and which has side walls which converge toward the upper surface of the body to define an elongated opening in the upper surface for the recess, a pair of clamping jaws within said recess which are of approximately the same length as the recess and are of substantially uniform cross-section throughout their lengths, each of said jaws having an outer inclined face adjacent and parallel to one of the converging walls of the recess and said jaws having inner adjacent faces substantially parallel to each other between which the edge of a sheet of metal is adapted to be placed, and fluid pressure means disposed within the body of each clamp for moving the clamping jaws toward the opening for the recess whereby the converging walls of the recess force the jaws toward each other to clamp the edge of the sheet of metal therebetween, the inclined faces of the jaw members and the converging walls of the recess being so disposed with respect to each other that during movement of the jaw members toward the opening for the recess the inner faces of the jaw members remain substantially parallel, and hydraulic control means whereby the jaw-moving means of all of the clamping devices may be operated simultaneously and to the same extent.

2. A clamping device according to claim 1, in which the means for moving the clamping jaws comprises a cylinder arranged within the body of the clamping device below the bottom of the recess therein, a piston disposed within the cylinder and one end of which engages the lower faces of the jaw members, and means for introducing fluid under pressure into the cylinder to cause movement of the piston and the jaw members toward the opening of the recess.
